UNITED STATES PATENT OFFICE.

LEONARD LORD ELDEN, OF DORCHESTER, MASSACHUSETTS, ASSIGNOR, BY MESNE
ASSIGNMENTS, TO GENERAL ELECTRIC COMPANY, A CORPORATION OF NEW
YORK.

CIRCUIT-BREAKER.

1,145,235.

Specification of Letters Patent.

Patented July 6, 1915.

Application filed October 11, 1904. Serial No. 228,040.

To all whom it may concern:

Be it known that I, LEONARD LORD ELDEN, a citizen of the United States, and resident of Dorchester, Massachusetts, have invented an Improvement in Circuit-Breakers, of which the following description, in connection with the accompanying drawings, is a specification, like letters on the drawings representing like parts.

10. My invention is an improved automatic circuit breaker, the main object thereof being to provide a circuit breaker which is especially suitable for extremely heavy currents and which shall be very easy to operate.

It is well known that, especially in closing the usual automatic circuit breaker, considerable strength and power are required because of the heavy springs and other automatic opening and tripping means whose resistance has to be overcome before the circuit breaker can be properly closed, and this resistance is so great in very heavy-current circuit breakers as to tire and lame the operator, frequently requiring both hands and all his strength to close them. Accordingly I have devised a construction in which the latch or means for holding the switch closed, is not required to overcome or resist any opposing spring or opening device, but is free and unrestrained, so that it can be readily operated, the switch being held closed by a toggle on a dead center which constitutes an important feature particularly adapting the switch to automatic circuit breaking mechanism and renders it thus extremely sensitive, or by other suitable mechanism. The latching device serves mainly simply to hold the gravity device in position to operate when tripped.

My invention includes other important features, such as the maintenance of the shunt or carbon contacts closed until after the bridge contacts are broken, the carbon contacts being independently held together until after the latter contacts are broken, the mounting of said main and shunt contacts on independently pivoted arms having spring connection, a separate gravity, quick-opening handle, the arrangement of an opening movement through a series of momentum-giving impacts, provision for the automatic alinement of the laminated or bridge contact, besides various constructional improve-

ments to prevent heating, simplify the operation, repair and assemblage of the apparatus.

Further advantages and the operation of my invention will be pointed out in the course of the following description, reference being had to the accompanying drawings, in which I have shown one embodiment of my invention.

In the drawings: Figure 1 is a view in side elevation showing my improved circuit breaker in fully opened position. Fig. 2 is a diagrammatic view representing the toggle action, closed in full lines, and partly open in dotted lines, said dotted position showing the intermediate position of the bridge-carrying parts at which the separating cam-action takes place for quickly separating the carbon or shunt contacts. Fig. 3 is a transverse sectional view taken on the dotted lines 3—3 Figs. 7 and 8. Figs. 4 and 5 are details in side elevation showing the portions of the levers which actuate the shunt contact. Fig. 6 is a detail in top plan showing the bridge connection. Fig. 7 is a top plan view of the apparatus, Fig. 8 is a view in side elevation, parts being broken away, and Fig. 9 is a longitudinal sectional view on the dotted line 9—9 Fig. 7.

For convenience of illustration I have indicated a base 1 (which may be a switch-board or any other insulating slab or plate) to which contact blocks 2, 3 are secured, the former carrying a carbon contact 4 in its upper end, and a binding post 5 at its rear side, and the latter being connected with a heavy coil 6 inclosed in an iron case 7 and provided with a binding post 8 at its rear side.

At its upper end the case 7 as best shown in Figs. 3 and 8, has ears 9, to which are secured the outer ends 10 of a bracket 11 in which is pivoted at 12 a latch 13 in position above an opening 14 to be engaged by a tripping pin on the upper end of a movable core or armature 15 slidingly mounted in a tube 16 whose threaded upper end 17 is removably screwed into the case 7. The bracket 11 occupies a recess 18 formed in the contact block 3 and is provided so as to permit the latch 13 to be as long as possible, said latch 13 extending forward in position to engage a catch 19 projecting forward from a handle 20 pivoted at 21 to the case 7 and having a

weighted outer end 22 overhanging sufficiently to give a slightly falling tendency thereto when closed.

Coöperating with the contact blocks 2, 3 is a laminated bridge or contact maker 23 pivotally mounted on a pin 24 at the free ends of a pair of arms 25 freely pivoted at their inner ends on bolts 26 to the opposite sides of the case 7. The bridge is operated by a toggle consisting of links 27 pivoted respectively at 28 to the bridge-carrying arms 25, and a lower link or toggle member 29, U-shaped in cross-section as clearly shown in Fig. 3, where it will be seen that it is engaged at its opposite sides by projecting flanges 30 of the handle 20 when it is desired to close the circuit breaker. The aforesaid parts are so related that when the toggle is on a dead-center the circuit breaker is closed and its contacts are so maintained solely by said toggle in such sensitive position, *i. e.* on dead-center. This is one of the leading features of novelty to which the easy closing is due. Also the easy opening 25 of the circuit breaker is largely made possible and greatly facilitated by the same provision of having the contacts held closed by a toggle, whose normal switch-closed position is the dead-center position. This feature also particularly adapts the invention to automatic circuit breaking mechanism. The handle terminates in a shoulder 31 at its lower end and the toggle member 29 is provided with projecting lugs 32 in position 30 to be engaged by said shoulder 31, whereby the toggle is thrown from its dead center holding-position as shown in full lines in Fig. 2 to its broken positions as shown in Fig. 1 and in dotted lines Fig. 2. Beneath the handle, the case 7 is provided with a projection or rest 33 having a buffer spring 34 to receive the blow of the falling parts when the switch opens.

The bridge 23, as already mentioned, is pivoted at 24 and is capable of a limited swinging movement for permitting it to adjust itself in proper alinement with the contacting surfaces of the blocks 2, 3 as indicated in Figs. 1 and 8. The construction permitting this movement is shown more clearly in Fig. 6 where it will be seen that the laminated portion of the bridge 23 is carried on a hub 35 having projecting edges 36 extending beneath the arms 25 so as to leave a slight space 37 for the desired swinging or rocking movement.

Coöperating with the carbon block 4 is an opposite carbon block 38 mounted in the outer ends of a pair of arms 39 pivoted to swing freely on the bolts 26 already mentioned. The blocks 4, 38 constitute main shunt contacts and are normally held together by a spring 40 secured at 41 to the hub 35 of the bridge contact. Instead of permitting the spring 40 to bear directly

upon the adjacent shunt contact, I provide an insulating plate 42, this insulation of the spring preventing the latter becoming heated by current which would otherwise flow therethrough. At their inner ends and adjacent faces the arms 25, 39, are provided with coöperating cam surfaces or shoulders 43, 44, which permit the arms 25 to fall from their full line position Fig. 2 to their dotted line position before their shoulders 43 strike against the shoulders 44 and thereby compel the arms 39 to swing with the arms 25 the rest of the distance. An auxiliary shunt contact 45 is carried by a spring 46 on the bridge for extra precaution 80 against sparking in handling heavy currents. At the opposite sides of case 7 are barrels 47 containing plungers 48 held under upward tension against the ends 50 of arms 25 by small springs 49, these small 85 springs being solely for giving momentum to the moving parts upon the breaking of the toggle.

The armature tube, as already stated, is held in threaded engagement at its upper 90 end with the case 7, thereby permitting its instant removal when desired, and a further feature of simplicity thereof resides in running the slot 51 thereof down to the very bottom end where the tube is provided with a peripheral groove 52 into which is snapped a spring wire or split ring 53 for retaining the core or armature 15 and a regulating clamp 54 which may be loosened and slid up or down on the tube, and then clamped 100 fast, for stopping the pin 55 of the core or armature 15 and thereby regulating the distance to which said armature can fall, thereby determining the strength of current required for tripping the circuit breaker. 105

In use, it will be evident, viewing Fig. 1, that, although the present circuit breaker is capable of handling extremely heavy currents, it can be operated with very slight exertion. Let us suppose that the circuit breaker is open as shown in Fig. 1 and that it is desired to close it. The operator simply grasps the handle 20 and swings it upward into the position in Figs. 8 and 9 without meeting any substantial resistance, excepting the mere weight of the moving parts. The handle 20 at its lower end contacts with the lower link 29 of the toggle and through the latter lifts the bridge contact and shunt contact, the bridge contact being lifted by the direct connection of the toggle links 27 with the arms 25, and the shunt contact 38 being lifted by the engagement of the spring 40 with the insulating plate 42 thereof. As the bridge 23 strikes against its contacts it automatically adjusts itself to proper alinement because of its pivotal connection, and as the parts are brought into complete circuit-closing position the toggle 27, 29, is brought to dead-center po- 120 125 130

sition, thereby retaining the circuit breaker positively closed. This retention however, is not against the opening tendency of a heavy spring as is ordinarily the case. The parts are simply held in closed position by the vertical, dead-center position of the toggle acting independently and not acted upon by any other part. The handle is retained by the engagement of its catch 19 by the gravity latch 13. When an over load occurs the solenoid acts upon its armature 15 to raise the same quickly, thereby lifting the latch 13. This permits the weighted lever 20 to fall, and, upon reaching the full-line position Fig. 2, its shouldered end 31 strikes a hammer blow against the lugs 32 of the toggle, thereby readily breaking the toggle from its dead-center position and permitting the parts to fall in the order of movement presently described. It will be observed that the automatic tripping of the latch and handle has no effect on the toggle but that the latter maintains the parts exactly as before until the handle strikes the blow just described. The handle still has some distance to fall, and accordingly it imparts its momentum to the toggle and connected parts, this gravity action thereby taking the place of the usual heavy spring. The small springs 49 have no influence whatever excepting to accelerate the movement of the parts when once started. The latch simply holds up the handle 20, and hence is tripped by an exceedingly light and delicate upward impact of the armature 15. The spring 40 positively holds the carbon shunt-contacts in closed position until after the bridge contact and its auxiliary shunt have entirely separated from the contact blocks 2, 3, and thereupon, the bridge 23 and arms 25 having reached the position shown in dotted lines in Fig. 2, the shoulders 43 of the arms 25 come into sudden contact with the shoulders 44 of the arms 39 and thereby transmit a hammer-like blow to the latter, forcibly separating the shunt contacts 4, 38 and throwing the latter down against the spring 40, in position to be again raised when it is desired to close the circuit breaker next time.

Besides the easy closing, which is the main object of my invention, another purpose of the invention is to provide a light-weight opening so that the destructive pounding which is so injurious in many high service circuit breakers, is avoided. Not only are the parts operated simply by gravity and light in weight themselves, but the fall is divided into a series of impacts instead of one. The parts 31, 32, 43, and 44 constitute impulse-giving devices for delivering by gravity a series of opening impacts for opening the circuit breaker. The weighted handle 20 first strikes the toggle in the full line position Fig. 2, and then

strikes the buffer spring 34, this impact being immediately succeeded by that of the arms 25 against the arms 39, and then by the striking of the toggle link 29 against the now stationary handle 20 and finally the striking of the shunt contact against the spring 40. These impacts come in quick succession, almost simultaneously, but yet sufficiently separate to materially minimize the jar on the apparatus. This is aided or made possible in part by having the carbon shunt contact 38 and its independently pivoted carrying arm arranged for lost motion with relation to the main contact carrying arm, and under a tendency at all times to open except for the restraint of the spring 40, and having the switch operating means arranged to connect only with the main contact carrying arm. This requires the simultaneous operation of the shunt and main contacts.

Various other advantages follow from the preferred construction which I have explained. For instance, if a new bridge is required, all that is necessary is to drive out the pin 24 whereupon the defective bridge can be removed and a new one put in its place with but a moment's delay. I have already mentioned the extreme simplicity of construction and adjustment of the armature and its tube. It will also be observed that all the steel and iron parts are mounted on the case 7 which receives the magnetic lines of force and acts as a conductor for the shunt circuit. Each part is removable without disturbing the other parts, and there is no delicate mechanism to break or wear out.

I am aware that many changes in form and arrangement of parts may be resorted to without departing from the spirit and scope of my invention and accordingly I do not limit the latter excepting as expressed in the claims, reference being had to the foregoing description and drawings.

Having fully described my invention what I claim as new and desire to secure by Letters Patent of the United States, is:

1. A circuit breaker comprising relatively movable cooperating contacts, restraining means for normally holding said contacts in engagement, an impact device actuated solely by gravity, and pivotally mounted to swing when released to impart a blow to said restraining means and thereby permit said contacts to separate, said gravity device being normally held with its center of gravity substantially vertically above its pivot so as to have a slight but constant tendency to swing into tripping position solely because of its said position, a latch normally holding said gravity device against falling, and means responsive to an abnormal current condition for tripping said latch.

2. A circuit breaker, comprising separable

contacts, a toggle holding said contacts closed when on the dead-center, a gravity device for breaking said toggle, a latch normally holding said gravity device against falling, and means operated by an abnormal current condition for tripping said latch.

3. A circuit breaker, comprising separable main contacts, a toggle standing normally approximately vertical in position to be readily tripped and fall by gravity, a gravity member for operating the toggle, and a tripping device for releasing said gravity member actuated by an abnormal current condition, said contacts being held closed solely by said toggle.

4. A circuit breaker, comprising separable main contacts, a tripping device for releasing a gravity member actuated by an abnormal current condition, a toggle normally raised into approximately vertical position, and said gravity member extending normally upward along one member of the toggle in position to open the toggle by gravity when released by said tripping device, said contacts being held closed solely by said toggle.

5. A circuit breaker comprising separable main and shunt contacts biased to separate, a normally positive collapsible toggle for holding said contacts in engagement, an impact tripping member movable into tripping position to collapse said toggle and exert a circuit opening impulse on said toggle and contacts, said member being biased to tripping position to an extent which increases as it approaches tripping position, a latch for normally restraining said tripping member, and electroresponsive means for actuating said latch to release said impact member in response to an abnormal current condition.

6. A circuit breaker comprising separable contacts, a normally positive collapsible toggle connected to said contacts to hold them in closed position, a pivoted impact member movable into tripping position to collapse said toggle and exert an opening impulse on said contacts, said member being mounted to be slightly biased from normal position and to exert when in tripping position a much greater bias tending to collapse said toggle, and electroresponsive tripping mechanism for holding said member in normal position and for releasing said member in response to abnormal current conditions to permit said member to move into tripping position.

7. A circuit breaker comprising separable contacts, a normally positive toggle pivotally connected to one of said contacts and normally in position to hold said contacts closed, an impact member actuated solely by gravity and pivotally mounted to swing into position to strike said toggle a blow to collapse it and exert a quick circuit open-

ing impulse upon said contacts, an unrestrained latch for normally holding said member substantially vertical above its pivot and operating to release said gravity actuated member and permit it to fall into position to strike said toggle and accomplish said quick opening, and means operated by an abnormal current condition for operating said latch to release said member.

8. A circuit breaker, comprising separable contacts, a tripping device actuated by an abnormal current condition, and gravity mechanism containing a plurality of parts for giving a succession of distinct opening impulses for increasing the momentum of the separating contacts.

9. A circuit breaker, comprising separable contacts, a toggle for maintaining them closed when on a dead-center, and a gravity device for breaking said toggle by a gravity blow, the aforesaid parts containing a plurality of co-operating impulse-giving devices for delivering by gravity a series of opening impacts for opening said circuit breaker.

10. A circuit breaker, comprising separable contacts, carrying members therefor, means for holding said carrying members in closed position, and an operating handle normally tending to fall by gravity when the circuit breaker is closed, all of the movable parts above mentioned being arranged to fall by gravity from closed position, and a rest for supporting said parts in fallen position, the aforesaid mechanism containing means causing said parts to fall at distinct intervals and to transmit their weight to said rest in a series of separated impacts.

11. A circuit breaker comprising a bridge contact, an independently movable and separately mounted shunt contact, gravity tripping mechanism comprising a gravity impact member mounted to move by gravity when released, and connections between said impact member and said contacts to cause said impact member during its gravity movement to impart an opening impulse to said bridge contact and to thereafter move said shunt contact to open the circuit.

12. A circuit breaker, constructed for easy closing and easy opening, comprising separable contacts, and moving mechanism including carrying members for moving said contacts to closed position, said moving mechanism being constructed and arranged to move said contacts into contact-making position unretarded except by gravity, said moving mechanism including a toggle having a normal dead-center position and arranged to maintain said contacts in contact-making position when on a dead-center, and a gravity handle for operating said toggle tending to fall by gravity when the cir-

cuit breaker is closed, and automatic tripping mechanism for releasing said gravity handle.

13. A circuit breaker, comprising stationary main contact terminals located one above the other, a stationary shunt contact disposed above the upper main contact, a movable laminated bridging member for engaging said main contacts, a pivoted arm supporting said laminated bridging member in position to tend to fall by gravity when the circuit breaker is closed, switch operating mechanism connected only with said pivoted arm and comprising restraining means connected to said arm to hold it in circuit closing position, a second pivoted arm movable independently of said first mentioned arm and in position to tend to fall by gravity when the circuit breaker is closed, a movable shunt contact carried by said second arm and adapted to engage said stationary shunt contact, a spring carried by one of said arms and extending to the other of said arms for holding said shunt contacts in engagement when the circuit breaker is closed, a gravity impact member mounted to fall and engage said restraining means and thereby release said first mentioned pivoted arm, and automatic tripping mechanism normally restraining said impact member and responsive to an abnormal current condition for releasing said gravity member to fall and open the circuit breaker.

14. A circuit breaker comprising stationary main contact terminals located one above the other, a stationary shunt contact disposed above the upper main contact, a movable laminated bridging member for engaging said main contacts, a pivoted arm supporting said laminated bridging member, switch operating mechanism connected only with said pivoted arm and comprising restraining means for holding said arm in circuit closing position, a movable shunt contact movable independently of said first pivoted arm and always biased to move away from said stationary shunt contact, a spring carried by said arm and engaging the movable shunt contact to hold said movable shunt contact in engagement with the fixed shunt contact while said arm is in circuit closing position, and electroresponsive tripping mechanism for engaging said restraining means to release said pivoted arm and bridging member and thereby open the circuit breaker.

15. A circuit breaker, comprising stationary main contact terminals located one above the other, a stationary shunt contact disposed above the upper main contact, a movable laminated bridging member for engaging said main contacts, a pivoted arm supporting said laminated bridging member, a switch operating toggle connected only with said pivoted arm and overset when said arm

is in circuit closing position, a second pivoted arm movable independently of said first mentioned arm, a movable shunt contact carried by said second arm and adapted to engage said stationary shunt contact, both of said arms being mounted to always tend to fall by gravity from closed position, automatic releasing means to permit said fall, a spring carried by one of said arms and engaging the other of said arms to hold said second pivoted arm in closed position against gravity, energy storing tripping means for positively undersetting said toggle when released, and electroresponsive means for releasing said tripping means upon occurrence of predetermined conditions in the circuit.

16. A circuit breaker, comprising main contacts, shunt contacts, restraining means for holding the movable contacts in closed circuit breaker position, and operating mechanism for all the aforesaid parts and for aiding the circuit breaker to open, including current-actuated tripping means to release said restraining means, and an operating handle, and means movable with the main contacts and independent of the operating handle for holding said shunt contacts independently closed until after the main contacts are separated, said shunt contacts being at all times under tendency to open excepting for the restraint of said means which is movable with the main contacts.

17. A circuit breaker, comprising separable contacts including a bridge contact and a shunt contact, pivoted arms for carrying said bridge contact, independently pivoted arms for carrying said shunt contact, and a gravity device arranged to operate said arms by its gravity movement, said gravity device being normally in a position tending by gravity to move into open position.

18. A circuit breaker, comprising separable contacts including a bridge contact and a shunt contact, pivoted arms for carrying said bridge contact, arms pivoted independently of said other arms for carrying said shunt contact, yielding connection between said arms for causing said two contacts and their arms to move dissimultaneously, a toggle connected to said bridge carrying arms for maintaining said contacts in closed position when the toggle is on a dead-center and having said dead-center position as the starting position from which the circuit breaker is opened, and opening means for disturbing said toggle from said dead-center position to open the circuit breaker.

19. A circuit breaker, comprising separable contacts, a tripping coil, a metal case inclosing said coil and provided at its forward lower end with a projecting rest, falling contact-carrying arms, and operating means pivoted directly to the upper end of

said case and delivering their falling impact on said rest.

20. A circuit breaker, comprising vertically arranged fixed contacts, coöperating 5 movable contacts, a tripping coil, a metal case inclosing said coil, carrying arms for said movable contacts pivoted to said case, a gravity member, a toggle operating between said member and said arms, for maintaining 10 said contacts closed when in dead-center position, and a rest projecting from said case for receiving the impact of said gravity member, whereby all the movable parts are carried by, and their gravity impacts received by, said case.

21. A circuit breaker, comprising separable contacts, means for closing said contacts, including a toggle, and a handle for operating said toggle, said handle being 20 pivoted co-axially of said toggle but capable of swinging freely independently thereof, and provided with means for removably engaging the lower link of the toggle substantially throughout its entire length.

25. 22. A circuit breaker, comprising fixed contacts, a bridge for spanning them, pivoted arms carrying said bridge, a toggle for operating said arms, and a handle for operating said toggle, said toggle and handle 30 having complementary parts to interlock said handle and one link of said toggle against relative lateral displacement during toggle straightening movement, and thereby give strength and precision of circuit-closing movement to said toggle.

23. A circuit breaker, comprising separable contacts, an automatic tripping mechanism therefor including a coil, a movable core, a case surrounding said coil and core, 40 and a depending tube extending vertically through said case and entirely inclosing said

core, said tube having threaded engagement with the upper end of said case for instant removal therefrom when desired.

24. A circuit breaker, comprising separable contacts, an automatic tripping mechanism therefor including a coil, a movable core, and a tube extending vertically through said coil and inclosing said core, 45 said tube having an open lower end, and a spring retainer for preventing the escape of said core while permitting the quick removal thereof when desired.

25. A circuit breaker, comprising separable contacts and automatic tripping mechanism therefor including a coil, a movable core, a case surrounding said coil and core, and a tube containing the latter, said tube having threaded engagement with said case for instant removal therefrom when desired, 50 said tube having a longitudinal slot opening at the lower end thereof and a spring band surrounding said lower end for closing said slot, while permitting the quick removal of the core when desired.

26. A circuit breaker, comprising separable contacts including a bridge contact and a shunt contact, independent arms for said two contacts, a toggle for holding them closed, and a gravity member for operating said toggle, the bridge contact arms having means for giving a blow to the shunt contact arms after the bridge contact arms have opened the bridge.

In testimony whereof, I have signed my 75 name to this specification, in the presence of two subscribing witnesses.

LEONARD LORD ELDEN.
